CLAIM

The ornamental design for a container for fluids, as shown and described.

DESCRIPTION

FIG. 1 is a bottom perspective view of a container for fluids showing my new design;

FIG. 2 is an elevational view thereof;

FIG. 3 is a top plan view thereof;

FIG. 4 is a bottom plan view thereof;

FIG. 5 is a bottom perspective view showing a modified form of my new design;

FIG. 6 is an elevational view thereof; and

FIG. 7 is a top plan view thereof.

FIG. 1

FIG. 2

FIG. 3

FIG. 4

FIG. 5

FIG. 7

FIG. 6
